EDWARD E. WOOD, JR., OF NORTHAMPTON, MASSACHUSETTS.

FORK GUARD AND REST.

SPECIFICATION forming part of Letters Patent No. 318,070, dated May 19, 1885.

Application filed March 9, 1885. (Mccl.1)

To all whom it may concern:

Be it known that I, EDWARD E. WOOD, Jr., a citizen of the United States, residing at Northampton, in the county of Hampshire and State of Massachusetts, have invented new and useful Improvements in Guards and Rests for Forks, of which the following is a specification.

This invention relates to improvements in the construction and arrangement of guards and rests for forks, the object being to provide improved attachments of this class for forks, each of which is made separate from the other, but are operative in conjunction to be opened or closed, and whereby their operation is rendered easy and the guard and rest are adapted to be swung closely against the fork, thereby avoiding inconvenient projections.

In the drawings forming part of this specification, Figure 1 is a perspective view of a carving-fork having applied thereto a guard and a rest embodying my invention. Fig. 2 illustrates a part of a fork in side elevation, showing the positions of the guard and rest when closed against the fork. Figs. 3, 4, and 5 are views respectively of the rest, that part of the fork to which the guard and rest are pivoted, and the guard.

In the drawings, *a* is the shank of the fork, having thereon the laterally-projecting guard and rest-supports *c c*, and the shoulder *v*, having a face on a line with the rear edges of said supports. The supports are pierced transversely to permit of putting a pin through them, whereby the guard and rest are pivoted thereto, and behind the supports *c* the shank is faced off at *v*, the guard being of bifurcated form, as shown.

The rest *B* is connected by the end of its spring-tongue *d* with the shank *a* of the fork, the pivot-pin *z* passing through the supports *c* and the end of said tongue, the latter being between the supports. The said pin *z* is also the pivot of the guard *D*, its ends projecting far enough beyond the sides of said supports *c* to pass through the ends of the legs *o o* of the guard.

When the rest *B* and the guard *D* are hung to the shank *a*, as above described, the ends of the side bars, *e*, of the rest lie against the rear sides of the ends of the legs of the guard when the latter and the rest stand at right angles to the

shank of the fork, as shown in Fig. 1, the flat ends of the bars *e e* striking squarely against the face *v* on the shank, back of the supports *c*. The spring action of the tongue *d* of the rest *B* or of the bars *e*, or of both, whereby the ends of the bars, as aforesaid, press against the legs *o*, contributes to hold the guard up and swing it in both directions, according to whichever side of the pivot *z* the ends of the said bars are made to bear when the rest swings. The shoulder *v* on the shank co-operates with the bars *e* to maintain the guard in the position shown in Fig. 1. The face *v* on the shank *a*, against which the ends of the bars *e* strike, serves to arrest the backward swinging movement of the rest *B*.

One or both of the ends of the legs *o* of the guard *D* may have the cam-point *w* formed thereon; but the parts operate more smoothly with a cam on one leg, and the end of the other, *y*, rounded, as shown, thus leaving the end of one of the bars *e* to follow smoothly around the curved end *y* of the leg, and depending upon the other bar of the rest to act on the cam end *w* of the leg *o* and swing the guard.

To swing the guard from the position shown in Fig. 2 to that of Fig. 1, the rest is swung downward away from the fork, carrying the end of bar *e* gradually against the point only, of the cam *w*, the latter standing a little to one side of the pin *z*, and when the end of the leg reaches a point just behind the cam the end *w* of the leg below the pivot acts as a lever having its fulcrum on pin *z*, and the spring of the bar *e* upon it throws the guard up, and the latter and the rest snap simultaneously into their open positions. To close or swing down said parts, the rest is swung forward, and as soon as the bearing-point of the bar *e* is only against the point of cam *w* the guard swings downward and the two parts together take the positions shown in Fig. 2.

If desired, the arrangement of the rest *B* as to the tongue *d* and its bars *e* may be carried out in the construction of the guard, and the latter be connected with the rest, substantially as are the same parts, as shown, without departing from the spirit of this invention.

What I claim as my invention is—

1. A fork guard and rest consisting of a guard of bifurcated form pivoted at the ends

of its legs to supports on the shank of the fork, a rest having a tongue located centrally between two side bars, the end of said tongue being connected to the guard-pivot between 5 said supports, and the ends of said bars having a bearing against the ends of the guard-legs, combined with the shank of the fork and operating substantially as set forth.

2. In combination, the shank of the fork having the laterally-projecting supports *c c*, the shoulder *v*, and the face *v²*, the guard *D*, having the legs *o o*, one or both of which has the cam *w* thereon pivoted to said supports, and the rest *B*, having the bars *e e* and the 15 spring-tongue *d*, the latter being pivotally con-

nected to the shank between the legs *o* of the guard, substantially as set forth.

3. The combination, with the shank of a fork, of a guard and a rest, substantially as described, pivoted to said shank, both on the 20 same pivot, and having their pivoted ends engaging with each other and capable of swinging together to a position at right angles to the shank and thence downward toward the end of the fork upon the latter and its shank, substantially as set forth.

E. E. WOOD, JR.
